UNITED STATES PATENT OFFICE.

DANIEL A. DORAN, OF YONKERS, NEW YORK.

MAIL-BOX CONSTRUCTION.

Application filed November 9, 1923. Serial No. 673,688.

This invention relates to mail boxes and particularly to an improved mail box construction in which a plurality of independent and hinged mail boxes are mounted in a box proper, all of said boxes being coupled together to form a master door for said boxes, and the object of the invention is to provide a mail box construction of the class specified, the separate boxes of which are detachably mounted in connection with the main box member and pivotally mounted all on a common pivot and capable of independent movement; a further object being to provide means cooperating with all of said boxes and in connection with which the separate boxes are locked for moving all of said boxes together on the pivot thereof into open and closed positions and to form of all of the box members a master door construction; a further object being to provide a lock construction for controlling the opening and closing of all of the boxes in one operation, said lock cooperating with the box member or a part mounted in connection therewith; a still further object being to provide improved means for mounting a standard lock in connection with the master door construction; and with these and other objects in view the invention consists in a mail box of the class specified employing separate and independent lock controlled boxes coupled together in such manner as to form thereof a master door controlled by a government lock whereby one master and official key will operate the lock to control the admission to all boxes, as hereinafter more fully described and claimed.

The invention is fully disclosed in the following specification, of which the accompanying drawing forms a part, in which the separate parts of my improvement are designated by suitable reference characters in each of the views, and in which:

Fig. 1 is a sectional view through my improved mail box construction indicating the method of its use;

Fig. 2 is a face view of the mail box shown in Fig. 1 with part of the construction broken away and in section;

Fig. 3 is a section on the line 3—3 of Fig. 2;

Fig. 4 is a sectional detail view showing the method of mounting one of the locks which I employ; and,

Fig. 5 is a detail view of an attaching plate which I employ.

In the drawing I have shown for the purpose of illustrating one use of my invention a recess or compartment 10 cut in the wall 11 of a building, preferably in a hall or vestibule thereof, and at 12 I have shown my improved mail box construction. The mail box comprises a main box member 13 which is oblong and rectangular in form and is composed of top, bottom, side and back walls, and this box is adapted to be placed in the recess 10 secured in position by screws or the like 14.

Secured to the front lower edge portion 70 of the box member 13 and extending longitudinally thereof is a rod 15 with which a plurality of independent mail boxes 16 are pivotally connected. The mail boxes 16 are oblong and rectangular in form and are composed of front and back walls 17 and 18, side walls 19 and bottom walls 20. The bottom and side walls 20 and 19 of the separate boxes are recessed as shown at 21 to engage and span the rod 15 which forms a pivotal connection of the boxes 16 in the main box member 13. The side walls of the mail boxes 16 are curved as shown at 22, and the back walls 18 extend above the rear curved ends 22 of the side walls 19 as shown 85 at 23 to form stops which limit the outward movement of the mail boxes with reference to the main box member 13.

Mounted transversely of the main box member 13 and over the mail boxes 16 is a 90 plate 24 L-shaped in form in cross section, one part 25 thereof being arranged in the same plane as the front walls 17 of the boxes 16, and the other part 26 being directed inwardly at right angles to the part 25 and at 95 the lower edge thereof, the part 26 being provided with a plurality of apertures 27 through or in connection with which the lock bolts or latches 28 by independent locks 100 29 are adapted to operate for locking the separate mail boxes 16 in connection with the plate 24. Secured to the opposite ends of the plate 24 or to parts 30 bent at right angles to the part 25 of the plate 24 are side plates 31 which are so formed as to fit within the side walls of the main box member 13 and the top edges of the plate 31 are curved 105 as shown at 32 in Fig. 1 of the drawing, and the inner top corners of said plates are off-set as shown at 33 to limit the outward 110

movement of said plates in the main box member 13. The rod 15 passes through the front lower corner portions of the side plates 31 as shown at 34 in Fig. 2 of the drawing 5 to permanently couple said side plates with the main box member 13 and yet provide for the pivotal coupling of said plates on the rod 15.

Secured to the inner face of the plate 24, 10 or the part 25 substantially centrally thereof, is a plate 35 which may be secured to the plate 24 by spot welding or otherwise and countersunk in the plate 35 are the head ends of screws 36 which project a predetermined 15 distance beyond the inwardly directed face of the plate 35 and upon which an official Government lock 37 is adapted to be mounted, the lock being provided with apertures through which the screws 36 pass. Nuts 38 20 are employed for holding the lock 37 in position. The plate 24 as well as the plate 35 are apertured as shown at 39 to permit the passage of the lock cylinder 40 through said plates to permit of the insertion of an official 25 key through the key aperture 41 in the cylinder 40.

The bolt or latch 42 of the lock 37 is 30 adapted to operate in connection with an apertured latch plate 43 mounted in connection with the inner face of the top wall of the main box member 13 as clearly shown in Figs. 1 and 2 of the drawing, and it will be understood that the latch plate 43 may be formed integral with or secured to 35 the main box member.

With my improved mail box construction it will be apparent that the mail box may be installed in a suitable building or compartment provided in the building, and by reason 40 of the mounting of the lock 37 which is provided a properly authorized party may mount in connection with the mail box construction an official lock, the key of which is to be carried by the postman or other authorized parties. In the delivering of mail 45 the lock bolt 42 is moved into inoperative position by the operation of the lock by means of the proper key, and the plate 24 together with all of the mail boxes 16 is 50 swung outwardly as indicated in dotted lines in Fig. 1 of the drawing, and the mail to be delivered is inserted in the separate boxes 16, the ownership of which may be designated by suitable name plates applied to the 55 boxes themselves or to a finishing strip 44 surrounding the outer edge of the main box member 13, the name plates being preferably applied to the top transverse finishing strip. After all of the mail has been inserted in the 60 separate boxes and the box is closed and locked by moving the plate 24 and mail boxes 16 back into the position shown in full lines, the mail in the separate boxes may be removed by the owners of such boxes or the 65 parties renting the same by the use of keys

which will open the separate and independent locks 29, and in this operation it will be understood that the separate boxes are swung outwardly on the pivot rod 15 which is substantially the position shown in dotted lines in Fig. 1, but the plate 24 remains in its closed position and the mail is removed through the top or open ends of the boxes, the openings therein being large enough to facilitate the insertion of the hand into the box to remove the mail but, if desired, means may be provided for retaining short or small letters in predetermined position, or the separate boxes may be swung outwardly to such an extent to facilitate the removal of the mail therefrom.

It will be noted with my improved construction that I also provide a mail box of such length and depth as to receive all standardized first-class mail, such as letters, magazines and the like, and it will also be noted that the front faces of the boxes 16 are entirely closed or are not provided with the usual or commonly employed apertures or slots through which the mail is passed. On the other hand I provide mail boxes each of which constitutes a box member which is closed on all sides and at the bottom and the top only of which is open, but when said boxes are in their normal or closed position, they are entirely closed and contained within the main box member 13 thus providing a theftproof and fireproof mail box construction.

It will be understood that while I have shown the mail box construction in a unit constituting six independent mail boxes with means for interlocking said boxes to form thereof a master door member, any number of these boxes may be employed in a unit, 100 and on the other hand if a greater number of boxes are desirable the same may be made up in separate units, each unit containing a predetermined number of boxes, and while I have shown and described certain details of construction for carrying my invention into effect, it will be understood that I am not necessarily limited to these details, and various changes therein and modifications thereof may be made, within the scope of 105 the appended claims, without departing from the spirit of my invention, or sacrificing its advantages.

Having fully described my invention, what I claim as new and desire to secure by 110 Letters Patent, is:—

1. A mail box construction of the class described comprising a main box member, a plurality of independent mail boxes each of which are movably mounted in said main box member, and means for coupling all of 115 said mail boxes together and for moving the same in a unit relative to the main box member.
2. A mail box construction of the class de- 120

scribed comprising a main box member, a plurality of mail boxes each of which are movably mounted in connection with the main box member, said mail boxes comprising elongated box members open at the top thereof only, lock devices for the separate mail boxes, and means for coupling all of said mail boxes together to permit of the movement of said mail boxes as a unit relative to the main box member.

3. A mail box construction of the class described comprising a main box member, a plurality of mail boxes each of which are movably mounted in connection with the main box member, said mail boxes comprising elongated box members open at the top thereof only, lock devices for the separate mail boxes, means for coupling all of said mail boxes together to permit of the movement of said mail boxes as a unit relative to the main box member, and a lock mounted in connection with said last named means and cooperating with the main box member for locking all of said mail boxes in a closed position and within said main box member.

4. A mail box construction of the class described comprising a main box member, a plurality of mail boxes each of which are movably mounted in connection with the main box member, said mail boxes comprising elongated box members open at the top thereof only, lock devices for the separate mail boxes, means for coupling all of said mail boxes together to permit of the movement of said mail boxes as a unit relative to the main box member, a lock mounted in connection with said last named means and cooperating with the main box member for locking all of said mail boxes in a closed position and within said main box member, and means for detachably mounting said lock on its support.

5. A mail box construction of the class described comprising an oblong and rectangular main box member composed of top and bottom, side and back walls, a rod mounted transversely of the lower front edge portion of said box member, a plurality of independent supplemental box members pivotally mounted upon said rod and normally contained within the first named box member.

6. A mail box construction of the class described comprising an oblong and rectangular main box member composed of top and bottom, side and back walls, a rod mounted transversely of the lower front edge portion of said box member, a plurality of independent supplemental box members pivotally mounted upon said rod and normally contained within the first named box member, and means for coupling all of said supplemental box members together to constitute a unit thereof forming a master door for

closing the front open end of the main box member.

7. A mail box construction of the class described comprising an oblong and rectangular main box member composed of top and bottom, side and back walls, a rod mounted transversely of the lower front edge portion of said box member, a plurality of independent supplemental box members pivotally mounted upon said rod and normally contained within the first named box member, means for coupling all of said supplemental box members together to constitute a unit thereof forming a master door for closing the front open end of the main box member, a lock mounted in connection with said means and cooperating with the main box member for retaining all of said supplemental box members within the main box member, and each of said supplemental box members being provided with a lock cooperating with said means for independently locking the separate supplemental box members in connection therewith.

8. A mail box construction of the class described comprising an oblong and rectangular main box member composed of top and bottom, side and back walls, a rod mounted transversely of the lower front edge portion of said box member, a plurality of independent supplemental box members pivotally mounted upon said rod and normally contained within the first named box member, means for coupling all of said supplemental box members together to constitute a unit thereof forming a master door for closing the front open end of the main box member, a lock mounted in connection with said means and cooperating with the main box member for retaining all of said supplemental box members within the main box member, and for permitting of the opening of said supplemental box members independent of said means.

9. A construction of the class described comprising a casing; a plurality of receptacles open at the top and mounted to tilt into and out of said casing to be opened and closed thereby, said receptacles being mounted for movement simultaneously with or separately from each other; a master lock arranged to lock or release all of said receptacles; and an individual lock for each receptacle, substantially as described.

10. A construction of the class described comprising a supporting member; a plurality of receptacles mounted to move outwardly from said member; and means permitting the moving of all of said receptacles simultaneously or each individually, substantially as described.

In testimony that I claim the foregoing as my invention I have signed my name this 5th day of November, 1923.

DANIEL A. DORAN.
